AWNING

William I. Smith, Perrysburg, Ohio

Application November 4, 1954, Serial No. 32,960

Term of patent 14 years

(Cl. D21—6)

FIG. 1

FIG. 2

Fig. 1 is a perspective view of an awning, showing my new design, the opposite side having substantially the same appearance; and,

Fig. 2 is a fragmentary perspective view thereof, to an enlarged scale.

The characteristic feature of the design is shown in full lines.

I claim:

The ornamental design for an awning, as shown and described.

UNITED STATES PATENT OFFICE
CERTIFICATE OF CORRECTION

Design Patent No. 176,641

January 10, 1956

William I. Smith

It is hereby certified that error appears in the above numbered patent requiring correction and that the said Letters Patent should read as corrected below.

The above numbered patent was erroneously issued to the inventor, "William I. Smith", whereas said patent should have issued to --The Hettrick Manufacturing Company, of Toledo, Ohio, a corporation of Ohio--, as assignee of the entire interest.

Signed and sealed this 28th day of February 1956.
